RADIO RECEIVER CONTROL DEVICE

George Willard Thelin, Marion, Ind., assignor to
 Farnsworth Television and Radio Corporation,
 a corporation of Delaware

Application August 3, 1940, Serial No. 350,408

3 Claims.

(Cl. 74—90)

This invention relates to means for actuating variable control devices, and more particularly to a mechanism suitable for actuating a variable control of the type employed, for example, for the regulation of tone or volume in a radio receiver.

In previously-known arrangements in which the shaft of the variable control was arranged parallel with the panel of the receiver, the control was actuated by means of a disc mounted upon the control shaft and protruding through a slot in the panel. By contact with the knurled edge of the disc, the operator could adjust the variable control. Calibration and manipulation of such prior-art devices were difficult and unsatisfactory.

The present invention is directed to the problem of providing an improved means for actuating a variable control which is mounted with its shaft parallel to the panel of the receiver or other device, of which the control is a component part.

It is an object of the present invention to provide an actuating mechanism for a variable control by means of which a substantially linear movement of a control knob produces positive rotation of the shaft of the variable control.

An additional object is to provide an actuating mechanism for a variable control so arranged that the actuation may be performed by a motion functionally related to the effect of the control upon a system to which it is connected.

Another object of the invention is to provide means whereby a relatively short movement of the control knob produces rotation of the variable control shaft through a relatively large number of degrees.

A still further object of the invention is to provide positive means for indicating the setting of a variable control which is actuated by the linear movement of a knob, thus permitting accurate calibration of the variable control if desired.

In accordance with the present invention, there is provided a variable-control actuating mechanism which includes a lever slidably pivoted at one end about an axis parallel to the shaft of the variable control. A first member is mounted on the shaft of the variable control, and an arcuately-shaped second member engages the first member and is swivelly connected to the lever. The distance between the pivot of the lever and its point of swivel is so proportioned, with respect to the radius of the point of swivel on the second member, that the free end of the

lever moves in a substantially straight line. Additionally, the first and second members are so proportioned that rotation of the lever about its pivot through relatively few degrees produces rotation of the variable-control shaft through relatively many degrees.

For a better understanding of the invention, together with other and further objects thereof, reference is made to the following description taken in connection with the accompanying drawings, and its scope will be pointed out in the appended claims.

In the accompanying drawings:

Fig. 1 is a plan view, partly in section, of 15 a preferred form of the present invention;

Fig. 2 is an elevation, partly in section, taken on line 2—2 of Fig. 1;

Fig. 3 is a front view of a pair of control devices such as shown in Figs. 1 and 2; and

Fig. 4 is a circuit diagram, partly in block form, of a radio receiver incorporating two variable controls provided with actuating mechanisms in accordance with the invention.

Referring now more particularly to Figs. 1 and 25 2 of the drawings, there is shown a mounting bracket 1 which may be attached by any suitable means to the panel 2 of a radio receiver or the like. Lever 3 is slidably pivoted at one end to the mounting bracket 1 by means of the pin 4 which is free to move in the slot 5. The free end of the lever protrudes through a slot 6 in the panel 2 and carries at its outer end a knob 7.

The variable control 8 is secured to the bracket 1 by means of the mounting nut 9, and carries 30 on its shaft 10 a member 11, secured thereto. The arcuately shaped member 12 is pivotally secured to the bracket 1 by means of the pin 13, and its periphery is adapted to engage the periphery of the member 11. The lever 3 is 40 swivelly connected to the member 12 by means of the pin 14. A pointer 15 may be provided, and is attached to the knob 7 in such a manner as to extend slightly over the scale 16 which is secured to the panel 2 in a position paralleling 45 the slot 6, as more clearly shown in Fig. 3.

In operation, it will be apparent that the 50 tendency of the knob 7 to move away from the front of the panel 2, as it moves toward the position indicated by dotted lines at 7A in Fig. 2, is substantially compensated by the movement of the pin 4, away from the back of the panel 2. As a result, the pointer 15 lies substantially the same distance away from the scale 16 whether the knob be in the position indicated at 7, at 7A, or at 7B in Fig. 2.

It will also be noted that, since the effective radius of the member 12 is substantially greater than that of the member 11, a relatively small linear movement of the knob 7 produces an entirely adequate rotation of the shaft 10.

Although the members 11 and 12 are shown as having toothed peripheries, it will be understood that the edges of these members may be smooth, at least one of the surfaces being of resilient material, so that their engagement depends entirely upon friction, without departing from the scope of the invention.

The scale 16 may be calibrated in arbitrary units as shown in Fig. 3, or other means may be employed instead of or in addition to arbitrary units, to indicate the effect of moving the knob upon the performance of the system in which the variable control is employed. If the variable control is used as a tone control, for example, the scale 16 may be provided with a music color scale to indicate visually the effect of the tone control. Other means for calibrating the scale 16 will readily occur to those skilled in the art, and may be employed without departing from the scope of the invention.

Referring to Fig. 4, there is shown a radio receiving system comprising an antenna 17, a high-frequency selector and amplifier 18, a demodulator 19, a signal-repeating system 20, an output audio-frequency amplifier 21, a loud speaker 22, and a power supply 23. The signal-repeating system 20 includes a vacuum tube 24, a volume control potentiometer 25, a bass tone-control rheostat 26, and a treble tone-control rheostat 27. The rheostat 26 is shunted by a capacitor 28, and the junction of the rheostat 26 and the capacitor 28 is connected to the junction of the resistors 29 and 30 which are connected in series across a portion of the potentiometer 25. The rheostat 27 is connected in series with the capacitor 31 across the output terminals of the signal-repeating system 20.

It will be seen that the capacitor 28 and the resistor 29 are effectively in series across the potentiometer 25. Due to the reactance of the capacitor, the impedance of this shunting network increases with decreasing frequency, so that the signal voltage developed across the potentiometer 25, due to the substantially constant signal current from the demodulator 19, is greater at the lower audible frequencies than at the treble end of the musical scale. The effect of the capacitor 28 upon the frequency response may be varied by means of the rheostat 26. When the slider is at its uppermost position, the capacitor 28 is short-circuited and the low-frequency response is at a minimum. As the slider is moved downward, the impedance of the shunt network 28-29 to low frequencies becomes increasingly greater, so the low-frequency response is increased. Since the capacitor 28 has relatively low reactance at the higher frequencies, the treble response remains substantially unchanged.

The function of the resistor 30 is to prevent the impedance of the network 28-29 from rising too rapidly as the frequency decreases. The resistor 30 is connected to a tap on the potentiometer 25 so that the low-frequency accentuation is more pronounced at low settings of the potentiometer 25, thus compensating in the well-known manner for the deficiency of the ear at the lower volume levels.

The high-frequency response of the system is controlled by the rheostat 27. When the slider

of this rheostat is at its lowermost position, the attenuation of the treble response due to the capacitor 31 is maximum. As the slider is moved upward, an increasing resistance is inserted in series with the capacitor 31, so that its shunting effect is reduced and the treble response is increased. The value of the capacitor 31 is sufficiently small so that it has substantially no effect upon the low-frequency response of the system regardless of the setting of the rheostat 27.

In a preferred arrangement employing two controls in accordance with the invention, such as shown in Fig. 4, the bass tone control is preferably arranged to provide accentuation of the bass portion of the musical scale when its control knob is pushed downwardly, as indicated by the scale 16 of Fig. 3, and the treble tone control to increase the reproduction of high notes when its control knob is pushed upwardly as indicated by the scale 16A of Fig. 3.

Although the mechanism in accordance with the present invention may be made in a number of different forms and proportions, in one successful embodiment the following dimensions have been found satisfactory:

	Inches
Distance between pin 4 and outer end of knob 7	3.875
Distance between pins 4 and 14	1.657
Pitch diameter of member 11	0.562
Pitch diameter of member 12	2.812
Effective radius of pin 14 on member 12	1.093

In this particular embodiment, a two-inch linear movement of the pointer 15 provided a rotation of the shaft 10 of the variable control 8 of approximately 315 degrees, the lever 3 moving through approximately 36 degrees.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A variable-control actuating mechanism comprising a lever slidably pivoted at one end about an axis parallel to the shaft of said variable control, a first member mounted on said shaft, and an arcuately shaped second member engaging said first member and being swivelly connected to said lever, the distance between the pivot of said lever and its point of swivel being so proportioned with respect to the effective radius of said point of swivel on said second member that the free end of said lever moves in a substantially straight line.

2. A variable-control actuating mechanism comprising a lever slidably pivoted about an axis parallel to the shaft of said variable control, a first member mounted on said shaft, and an arcuately shaped second member engaging said first member and being swivelly connected to said lever, said first and second members being so proportioned that rotation of said lever about its pivot through relatively few degrees produces rotation of said shaft through relatively many degrees.

3. A variable-control actuating mechanism comprising a lever slidably pivoted at one end about an axis parallel to the shaft of said variable control, a first member mounted on said

shaft, and an arcuately shaped second member engaging said first member and being swivelly connected to said lever, said first and second members being so proportioned that rotation of said lever about its pivot through relatively few degrees produces rotation of said shaft through relatively many degrees, and the distance be-

5 tween the pivot of said lever and its point of swivel being so proportioned with respect to the effective radius of said point of swivel on said second member that the free end of said lever moves in a substantially straight line.

GEORGE WILLARD THELIN.
